UNITED STATES PATENT OFFICE

149,997

DESIGN FOR A LAMP

Charles F. Burkett, Cumberland, Md.

Application September 14, 1946, Serial No. 133,322

Term of patent 3½ years

(Cl. D18—20)

To all whom it may concern:

Be it known that I, Charles F. Burkett, a citizen of the United States, residing at Cumberland, in the county of Allegany and State of Maryland, have invented a new, original, and ornamental Design for a Lamp, of which the following is a specification, reference being had to the accompanying drawing, forming part thereof.

The characteristic features of my design reside in the portions shown in full lines.

I claim:

The ornamental design for a lamp as shown and described.

CHARLES F. BURKETT.
